(57) **CLAIM**

The ornamental design for a portable speaker, as shown and described.

DESCRIPTION

FIG. 1 is a top, front perspective view of a portable speaker, showing my new design;

FIG. 2 is a bottom, front perspective view of the portable speaker;

FIG. 3 is a top, rear perspective view of the portable speaker;

FIG. 4 is a bottom, rear perspective view of the portable speaker;

FIG. 5 is a front elevation view of the portable speaker;

FIG. 6 is a rear elevation view of the portable speaker;

FIG. 7 is a top plan view of the portable speaker;

FIG. 8 is a bottom plan view of the portable speaker; and,

FIG. 9 is a left elevation view of the portable speaker.

The broken lines in the figures illustrate the portions of design that form no part of the claimed design.
